UNITED STATES PATENT OFFICE.

GEORGE L. MARCUM, OF WILLIAMSON, WEST VIRGINIA.

CONSTRUCTION OF BILLIARD TABLES.

Application filed July 3, 1926, Serial No. 120,434. Renewed September 19, 1928.

The object of this invention is to provide a particular form of leveling device for a billiard table, and particular means for mounting the rail at the edge of the table, 5 and means for mounting and adjusting the covering or cushioning element.

A further object is to provide a hinged rail, detachable securing means therefor, and screw controlled clamping and adjusting means for engaging the covering or cushion. 10

With the foregoing and other objects in view, the invention consists in the novel construction and arrangement of elements described, illustrated and claimed, it being understood that modifications may be made within the scope of the claims without departing from the spirit of the invention. 15

In the drawings forming part of this application,

Figure 1 is a view of the table in side elevation.

Figure 2 is a detail view in top plan.

Figure 3 is a section on line 3—3 of Figure 1.

Figure 4 is a detail in section on line 4—4 of Figure 1.

Figure 5 is a fragmentary section on line 5—5 of Figure 3.

30 A slate top 10 is carried or mounted on a horizontal element 11, and a cover or cushioning element is designed 12, this cover passing over the rounded edge of the plate 10, and slightly below the lower edge of the latter, the extreme edge portion of the cover or cushion being clamped by strips or bars 14 and 15 operating in a channel portion 16 in supporting member 11. Screws 15' connect bars 14 and 15.

40 In order to vary the tension on the clamping means I provide screws or bolts 17 each passing thru and into an internally threaded element or sleeve 18 having a flange 19 by means of which it is retained in position, 45 in view of engagement with adjacent stationary elements, in the manner clearly illustrated in Figure 3. One of these stationary elements 20 is secured by bolts 24'. The head of bolt or screw 17 is positioned

50 within a recess 21 in rail 22, and the head or nut of bolt 24 is within another recess, the bolt last named passing thru rail 22, thru the covering 12, at the edge of the slate member, and the shank of the bolt last named passing into slate 10. Bolt 24 includes an engaging element 25 embedded in the body

of slate, so that it will maintain its position, and permit the rail 22 to be properly secured, while at the same time said rail is adapted to be swung outwardly about the 60 hinge connection 27, when it is desired to renew the cushion or covering.

Rail 22 includes an upper outward extension 22', and the latter is provided with a recess on the under side engaged by slideable 65 bolt or pin 28 having a beveled end, and acting under the influence of a spring 29. The door or outer section of the rail, designated 30, in which the slideable bolt is mounted at the upper edge, is movable about the 70 hinge connection 31 at the edge of the bottom section 32 of the rail. Element 32 is secured by bolt 34 passing thru an element of the box structure 35 and engaged by a nut 36 counter-sunk in a recess in said element 32. Box 35 has a removable portion 38 mounting a spring held catch or bolt 39 acting as a retaining member, and a pin 40 in the lower edge of element 38 engages a recess 41, for retaining the lower portion of door 38. A plate 42 extends transversely of box 35 and is supported in grooved portions 43, this plate resting on the upper edge of a structure 44 within box 35. A plate 46 is firmly mounted in the leg structure 44, 85 and a heavy screw 48 passes thru plate 42 and carries nuts 49 and 50 engaging opposite sides of the plate, permitting vertical adjustment. End portion 47 of screw 48 is secured to a boss on plate 46 by a transverse 90 pin 51. A molding 54 surrounds the structure 44, and engages shoulders 55 and 56 thereon. A cloth lining may be provided between the box 35 and the leg, but is not essential. The adjusting means just described, provides for the leveling of the 95 table, at the corner portions thereof.

The adjusting nuts 49 and 50 are accessible thru removable element or door 38, and when access is to be obtained to adjusting screws 100 or bolts 17, door 30 makes this possible. Moreover when the cushion or cover 12 is to be renewed, the rail 22 is movable outwardly about the hinge connection referred to, upon loosening the securing means 24. 105 The slideable bolts 28 and 39 are operated by means of knobs or the like designated 28' and 39', and adapted to project into slots 28'' and 39'', the ends of these operating elements being substantially flush with the 110 outer surface of the elements in which the slots are formed.

Overlapping corner plates 60 and 61, illustrated in Figure 2, are detachable when the rails 22 are to be released.

Having described the invention what is claimed is:

1. In a device of the class described, a table top and a cover therefor, a side rail engaging the edge portion of the cover opposite the edge of the table top, clamping means for the cover, and means for adjusting said clamping means and cover by moving the clamping means bodily below the top.
2. In a device of the class described, a table top and a cover therefor, a side rail engaging the edge portion of the cover opposite the edge of the table top, clamping means for the cover, means for adjusting said clamping means by producing slidable movement below the top, and means detachably connected with the rail for covering and protecting the adjusting means.
3. In a device of the class described, a table top and a cover therefor, a side rail engaging the edge portion of the cover opposite the edge of the table top, clamping means for the cover, means for adjusting said clamping means by producing slidable movement below the top, and a hinged door having its upper edge detachably connected with the rail, for covering the adjusting means.
4. In a device of the class described, a table top and a cover therefor, a side rail, means for hinging the rail about a horizontal axis, means for securing the rail in operative position alongside of the edge of the top and cover, clamping means for the edge of the cover, below said top, said clamping means including threaded devices and fabric engaging means.
5. In a device of the class described, a table top and a cover therefor, a side rail extending along the edge of the top and cover, means for hinging the side rail, hinged

means for covering the outer lower portion of the side rail, clamping means for the cover, movable below the table top, a horizontal supporting element below said top, and a strip extending longitudinally below the horizontal element and adapted to support the hingedly mounted elements.

6. In a device of the class described, a table top and supporting means therefor, a plate extending transversely of a fixed portion of the supporting means, a leg movable with reference to the fixed portion, a screw for effecting such movement, the screw passing thru the plate and being fixed with reference to the leg, and adjusting means co-operating with the screw and abutting the plate, said means last named comprising elements thru which the screw is threaded, and these elements being on opposite sides of the plate.

7. In a device of the class described, a table top and supporting means therefor, a plate extending transversely of a fixed portion of the supporting means, a leg movable with reference to the fixed portion, a screw for effecting such movement, the screw passing thru the plate, and adjusting means co-operating with the screw and abutting the plate, a block bearing on the upper end of the leg, and means rigidly connecting the block and screw.

8. In a device of the class described, a table top and supporting means therefor, a plate extending transversely of a fixed portion of the supporting means, a leg movable with reference to the fixed portion, a screw for effecting such movement, the screw passing thru the plate, adjusting means co-operating with the screw and abutting the plate, the fixed portion of the supporting means including a box like structure having a side opening, and a detachable closure for the opening.

In testimony whereof I affix my signature.
GEO. L. MARCUM.
